CARL A. SCHMIDT, OF NEW YORK, N. Y.

LOCKING MEANS FOR HOOKLESS FASTENERS FOR RECEPTACLES

Application filed March 16, 1928. Serial No. 262,074.

This invention relates to receptacles, such as bags, pouches, wallets and the like having an opening arranged with what is commercially known as "hookless" fastener means to close and retain the opening in closed condition wherein hook and eye fastener members are secured to the edge of a flexible tape attached to the marginal portions of the opening to the receptacle and movable into and out of interlocking engagement by a member 5 slidable on the flexible tape, said member when moved in one direction being adapted to move the hook and eye members into interlocking engagement and out of locking engagement when moved in the opposite direction, and it is the object of the invention to provide means to be mounted on said actuating member to serve as the manipulating means therefor and co-operate with the receptacle to lock the actuating member against movement when moved to position with the fastener member interlocked and in receptacle closing position, and to provide means for this purpose which is novel, simple and 15 cheap in construction and efficient in use.

In carrying out the invention the fastener actuating member has a pull device in the form of a perforated metal plate pivotally mounted thereon. The opening is arranged 20 at one side or end of the receptacle and in the fastener closing position of the actuating member it is located adjacent the juncture of a side and end of the receptacle. A hood of 25 rectangular shape having four integral sides is mounted upon the plate adapted to manipulate the same and to participate in the movement thereof. The hood is arranged to be positioned over a portion of the receptacle when the fastener members are in closed position 30 with equal portions of opposite sides of the hood contiguous to the sides of the portion of the receptacle enclosed by the hood. The opposite sides of the hood have aligned 35 perforations adapted to be positioned in register with aligned perforations in the portion of the receptacle enclosed by the hood for the engagement of a lock to secure the hood in said position.

In the drawing accompanying and forming 40 a part of this application, Figure 1 is a per-

spective view of a coin or cash bag arranged with hookless fastener means with an embodiment of my invention applied thereto and showing the same secured in closing position.

Figure 2 is a view of a portion of the right hand upper corner of the bag shown in Figure 1 looking at the top thereof and showing the securing means moved to inoperative position and the fastener actuating member adjusted to partially open the bag.

Figure 3 is a perspective view of the securing means in relation to a part of the fastener actuator member, and partly broken away to show the structure of the same; and

Figures 4 and 5 are cross sectional views of the securing means showing the method of mounting the same on the part of the fastener actuating member shown in Figure 3.

The invention is applicable to various types of receptacles, such as mail and parcel post bags and pouches of suitable material, such as fabric, leather and the like. I have shown the same in connection with a coin or cash bag adapted for use for the delivery of securities and negotiable documents by messengers, designated in a general way at 6, and having an opening thereto in one of the longitudinal sides, as at 7. The opening is arranged with hookless fastener means, in the present instance of the construction and arrangement shown in Letters Patent No. 1,243,458, and comprising hook and eye members 8 secured in spaced relation to the edge of a flexible tape 9 with the hook and eye members extending laterally from the tape and the tape attached to the wallet by stitching. The hook and eye portion of the fasteners are moved into interlocking engagement by a lateral flexing movement of the fastener carrying portion of the tapes spreading adjacent fasteners of the opposite tapes and in such condition interengaging the fasteners of one tape with the fasteners on the other tape, this being accomplished by a slider or actuator in the form of a cam member 11 slidably mounted upon the fastener carrying portion of the tapes and adapted to move the fasteners into interlocking engagement when moved longitudinally in one direction and out of locking engagement.

ment when moved in the opposite direction. To facilitate the manipulation of and impart sliding movement to the slider 11 a pull or finger grasping device in the form of a plate 12 is provided, said plate having a perforation at one end and a bifurcated portion 13 at the opposite end whereby it is mounted on a rib 14 extending longitudinally of the slider to have pivotal and sliding movement thereon.

To lock the slider in position with the fasteners in the bag closing position thereof, in which position it is at the extreme right hand end of the bag, as viewed in Figure 1, a hood member of rectangular box shape embodying opposite side portions 15, and end portion 16 and an integral side connecting portion 17 with the two opposed sides thereof having alined openings 18 therein is employed. The hood is fixed to the plate 12 in a suitable manner with the plate arranged within the hood and in contiguous relation to the connecting portion 17. This is accomplished in the present instance by perforating said connecting portion of the hood by offsetting inwardly the material stamped from the hood to form the opening, as at 19 in Figure 4, and engaging the offset material in the perforation of the plate 12 and flanging the same over the plate, as at 20 in Figure 5, so that the plate will lie in contiguous relation to the inner side of the connecting portion 17. The hood by such mounting will be united integral with the plate and participate in the movement of the plate laterally of the slider 11 and thus serve as the means to manipulate the slider or actuator and allow of pivotal movement of the hood relative to the slider. The free edge of the side connecting portion 17 of the hood is arranged with an indentation 21 to compensate for the projecting rib 14 of the slider 11 and permit of movement of the hood relative to the slider, and in the closing position of the slide permit of the hood being pivotally moved over the adjacent corner at upper and end portion of the bag with the sides of the bag and sides 15 of the hood contiguous to each other. The opposed sides of the hood converge from the connecting portion 17 for a short distance, as at 21', and then extend parallel to each other to the extremities thereof and when the hood is adjusted to engage over the corner of the bag the converging portions 21' of the walls will extend in spaced alinement with the fastener carrying tapes 9 and the parallel portions will lie contiguous to the sides of the bag to prevent access to the hood and tampering with the slider 11. The sides of the bag are arranged at the portion enclosed by the hood when the same is in slider enclosing position with perforations having an eyelet 23 extended therethrough and flanged over the marginal portions of the openings and thus connecting the sides of the bag around the

perforations. To secure the hood in slider enclosing position the shackle of a key operated padlock 22 is engaged in said perforations of the hood and bag.

By the arrangement of connecting the plate 12 with the hood said plate together with the movable connection thereof with the actuator 11 is enclosed by the hood when the latter is in securing position thus preventing the engaging of an implement between the legs of the plate bifurcation 13 to spread said legs to release the plate and securing hood from the actuator or slider and thus permit of the manipulation of said actuator to open the bag for the surreptitious removal of the contents thereof.

While I have described and illustrated what is believed to be the preferred embodiment of the invention which functions to efficiently carry out the invention, it will be obvious that modifications may be made in construction and arrangement of parts and come within the scope of the invention.

Having thus described my invention I claim:

1. In a receptacle having an opening arranged with co-operating releasable fastener members on the edges thereof and a fastener actuator slidable on the edges of the opening to move said fastener members to receptacle closing and opening position, a hood member movably connected with and arranged to be engaged over and enclose said actuator, said hood having alined perforations in opposite sides thereof adapted to be placed in register with perforations in the receptacle adjacent the opening at one end thereof when the actuator is in position with the fastener members in receptacle closing position, and said perforations adapted for the engagement of the shackle of a padlock to secure the hood in said position.

2. In locking means for fastener members for the opening of a receptacle as claimed in claim 1, wherein the hood is of rectangular shape connected with the actuator intermediate the opposite wall portions and said wall portions converging toward each other for a portion of the length thereof from said connecting portion and then extending parallel to the extremity thereof and having the alined perforations in the parallel wall portions, and said parallel wall portion being adapted to embrace and lie contiguous to the opposite sides of the receptacle with the hood perforations in alinement with the perforations in the receptacle.

3. In a receptacle of rectangular shape having an opening extending along one end thereof arranged with co-operating releasable fastener members on the opposite edges and a fastener actuator slidable longitudinally on the edges of the opening and operative when moved in one direction to move said fastener members to receptacle closing

- position and when moved in reverse direction move the fastener members to receptacle opening position, a hood pivotally mounted on the actuator to have movement relative thereto and having alined perforations in opposite sides, said hood being adapted to be engaged over the actuator and a corner of the receptacle to embrace a perforated portion of the receptacle with the actuator in position with the fastener members in receptacle closing position, and the hood adapted to be secured in said position by a padlock the shackle of which is engaged in the perforations of the hood and receptacle.
- 15 4. In a receptacle having an opening arranged with co-operating fastener members and an actuator to move the fastener members to receptacle opening and closing positions, a hood adjustably carried by the actuator to have movement in a direction toward and away from the receptacle and having alined perforations in opposite wall portions, said hood in the receptacle closing position of the actuator being adapted to be engaged over said actuator and a portion of the receptacle with the opposite perforated wall portions embracing opposite sides of a perforated portion of the receptacle, and adapted to be secured in said position by the shackle 30 of a padlock engaged in the hood and receptacle perforations to secure the hood in said position.

Signed at the city of New York, in the county of New York and State of New York, 35 this 10th day of March, 1928.

CARL A. SCHMIDT.
